UNITED STATES PATENT OFFICE.

CHARLES FORBES, OF ROCHESTER, NEW YORK.

MACHINE FOR GRADING FRUIT.

1,182,005.

Specification of Letters Patent.

Patented May 9, 1916.

Application filed October 20, 1911. Serial No. 655,813.

To all whom it may concern:

Be it known that I, CHARLES FORBES, a citizen of the United States, residing at Rochester, in the county of Monroe and State of New York, have invented a new and useful Machine for Grading Fruit, of which the following is a specification.

This invention relates to a fruit sorter or grader, by which apples, peaches, pears, and other like fruit may be separated into any number of desired sizes.

It belongs to that type of graders in which the fruit passes through a V-shaped slot: the smallest fruit passing first and the largest last.

The following is a description of the construction and operation of the apparatus.

Figure 1. is a side view of the machine with the front cut away through the line 20 A—A in Fig. 2. which is a top view or plan. Fig. 3. is an enlarged sectional view of the upper half of the cylindrical pulley through the line B—B. Fig. 1. Fig. 4. is an enlarged sectional view through the line 25 C—C Fig. 2.

In Figs. 1 and 2. the supporting framework is represented at 1—1—1—1 and the posts 2—2—2—2. In Figs. 1 and 2. a wide carrying belt is represented at 3—3 and passing around the two cylindrical pulleys 4—4. This belt may be guided by a row of blocks 5 &c., attached to its inner surface running in the groove in the pulley at 6 Fig. 3. and in the groove 6 in the supporting board at 9—9. Fig. 4. The tension of the belt is regulated by means of the bolts 7—7—7—7 which regulate the distance of the pulleys 4 and 4 apart. The upper or carrying fold of the belt is supported by 30 the supporting board 9—9 resting upon and extending from the cross bars 8—8 Fig. 1 seen in section Fig. 4. This supporting board slants downward laterally both ways from its middle. The belt is brought into 35 contact with the board by means of the depressors 10—10, Figs. 2 and 4. On each side of the wide belt 3—3 there is a narrow one. The relative position of each is represented by the dark lines 11—11 in the four figures. 40 Each may be traced from the cylindrical pulley 4 on the left to the small pulley 12 Fig. 1, thence downward around the right hand pulley 4, back to the starting point. In the upper part of the journey each belt 45 is guided and supported by the grooved supporting board 13, from 13 to 13. The sup-

porting board 13—13 is lengthened by the adjustable extension 14, Figs. 1 and 2. The tension of the belts is regulated by the bolts 15—15. The width of the V-shaped opening 60 is adjusted by raising or lowering the slotted support 16 Fig. 1. and secured in place by the bolt 17. On the surface of the left hand pulley 4. Fig. 1 are triangular projections represented by 18—18. The rotation of the pulley will result in the lower edge of the 65 hopper 19. being lifted by the contact of each triangular piece. If the triangular pieces are alternately placed at the ends of the pulley, the hopper will be given a tilting 70 motion; the frequency depending upon the number of triangular pieces.

The grader may be actuated by means of the crank 20 or the pulley 21. Fig. 2. These are interchangeable.

In Fig. 1, are loops 22—22—22 in canvas attached at the ends at 8—8. These loops receive the fruit as it passes through the grader. Their inclination should be such that the fruit will readily roll downward. 75 Cross pieces 23—23, are supports for the canvas. These cross pieces are in turn supported from the framework 1—1 by means of hooks 24—24. The number of grades and size of each into which the fruit is sorted 80 depends upon the number and width of the loops in the canvas or its equivalent.

In operating the machine proceed as follows. Set the machine in motion. Place the fruit into the hopper 19. The agitation 90 of the hopper by the triangular projections 18—18, will facilitate the movement of the fruit. The amount of agitation may be regulated by raising or lowering the front edge of the hopper. When necessary the flow 95 of fruit may be governed by the flap arrangement represented by 25, Fig. 1. After the passage of the fruit from the hopper it is carried forward by the belts, principally supported by the wide one 3. In this arrangement there is no rolling, sliding or jamming of the fruit. The fruit moves onward until each particular piece finds proper width between the V-shaped inclined belts, when it rolls from the inclined side of the 100 wide belt into the canvas receptacle below. When the fruit is irregular in shape like the pear, it is made to go lengthwise by the following arrangements. In one, the narrow carrying belts are made to go at a different speed from the larger belt. This is 105 accomplished by the pulleys of the narrow 110

belts having a different diameter from that of the larger belt, as illustrated at 11 and 3, Fig. 3. The other way which, is very efficient, is by means of an obstruction 26—5 Fig. 2 fixed rigidly to the guiding board 13—13. The projecting end of the fruit, will in its onward passage come into contact with the obstruction 26 and turn lengthwise in its course. This is illustrated with the 10 pear 27, Fig. 2. After the fruit has passed into the canvas loops 22—22—22 it may be allowed to be gathered into any convenient retainer. A very convenient way to dispose of the fruit is to allow it to pass into the 15 tray 30—30 Fig. 2. Partitions 31—31 may be placed across the tray to keep the grades of fruit separated. A similar tray may be placed on the opposite side. If the trays are hinged they may be allowed to hang down- 20 ward when not in use; and when in use sup- ported by supporting rods 32—32. The fruit in the trays is in a convenient position to be packed into baskets or any suit- able shipping vessel. It is evident that the 25 cylindrical pulleys 4—4 Fig. 1, need not be each in one entire piece. The portions car- rying the narrow belts may be separated from that carrying the wide belt. The sepa- ration may be made through the line 33—33, 30 as seen in Fig. 3. This will admit of the dis- tances between the small belts to be varied when an additional adjustment is desired in connection with the regular adjustment at 16—Fig. 1.

**Copies of this patent may be obtained for five cents each, by addressing the "Commissioner of Patents,
Washington, D. C."**

In Figs. 1 and 2, fruit is represented at 35 28—29. Carrying belts may be substituted for the canvas loops 22—22—22, Fig. 1, when the fruit has to be carried away from the grader.

Having described my invention what I 40 claim as new and desire to secure by Letters Patent, is—

1. A grader comprising a laterally in- clined conveying belt and a vertically di- verging grading belt coöperating therewith 45 and providing between the same a gradually expanding grading opening.

2. A grader comprising a bilaterally in- clined conveying and vertically diverging 50 grading belts providing gradually expand- ing grading openings between said convey- ing and grading belts.

3. A grader comprising a bilaterally in- clined conveying belt, a pair of vertically 55 diverging grading belts coöperating there- with and grooved supporting rails for said belts.

4. A grader comprising a bilaterally in- clined conveying belt, a pair of upwardly 60 diverging grading belts coöperating there- with, grooved supporting rails for said belts and adjustable supports for said rails, where- by the divergence of the grading belts may be varied.

CHARLES FORBES.
